UNITED STATES PATENT OFFICE.

WILLARD R. WALKER, OF SYRACUSE, NEW YORK, ASSIGNOR TO WALKER BROTHERS COMPANY, OF SYRACUSE, NEW YORK, A CORPORATION OF NEW YORK.

CULINARY BASKET.

Application filed January 19, 1921. Serial No. 438,379.

To all whom it may concern:

Be it known that I, WILLARD R. WALKER, of Syracuse, in the county of Onondaga, in the State of New York, have invented new and useful Improvements in Culinary Baskets, of which the following, taken in connection with the accompanying drawings, is a full, clear, and exact description.

This invention relates to certain improvements in culinary baskets or trays of the class set forth in my pending application #406,305 filed August 27, 1920 in that it is adapted to receive and support quantities of crockery dishes and other dining or kitchen utensils for transportation from one place to another but more particularly for supporting said utensils within the vat of a dish washing machine in such manner that the washing fluid may be impelled against all portions of the utensils until thoroughly cleansed and also allowing the dishes to drain until practically dry following the washing operation. That is, the tray or basket may be taken into the dining-room or other place where the soiled dishes are collected and properly placed in the tray which with the soiled dishes therein then conveyed to and placed within the vat of the washing machine where they are thoroughly cleansed and dried as previously stated whereupon the tray with the cleansed dishes therein may be removed from the vat and carried to the place for distribution of said dishes where the latter are removed and stored for future use thus permitting the empty tray to be reused in washing and drying other soiled dishes when desired.

The main object is to provide a tray or basket of this character which is light, strong and durable and capable of holding a large number of utensils in compact but spaced relation so that the washing fluid may pass freely through the basket and between and against all portions of the utensils.

The main body of the basket is preferably made of metal for strength and durability and one of the specific objects is to provide means for protecting the dishes against breakage when inserting them into and removing them from the basket.

A further object is to provide the tray or basket with a removable cage or supplemental tray for the reception of knives, forks, spoons and similar implements, thus permitting the supplemental tray to be easily

removed and replaced from and within the main basket without disturbing any of the other utensils.

Another object is to construct the upright, tangential partitions in such manner as to reduce to a minimum the area of contact of the dishes therewith or in other words, to bring the contacting points some distance inwardly from the marginal edges of the dishes so as to reduce the liability of chipping said edges in addition to reducing the contact area.

A further object is enable the tangential partitions to be utilized for supporting dishes for widely variable diameter edgewise vertically upon the openwork deck or bottom.

Other objects and uses relating to specific parts of the basket will be brought out in the following description:

In the drawings:

Figure 1 is a top plan of a culinary basket embodying the various features of my invention.

Figure 2 is an enlarged, transverse, vertical sectional view of the same basket taken on line 2—2 Figure 1.

Figures 3 and 4 are enlarged, detail sectional views taken, respectively, on lines 3—3, 4—4 Figure 1.

Figure 5 is the top plan partly in section of a portion of the upper marginal ring of the basket showing the manner of fastening the buffer ring thereto.

Figure 6 is a detail sectional view of portions of one of the buffer rings and its underlying supporting ring showing the manner of securing the spliced ends of the buffer ring together.

As illustrated, the basket is circular in top plan to correspond approximately to the interior diameter of a circular vat of the washing machine so that it may be inserted into and withdrawn from the open top of the vat with an easy sliding fit and comprises a series of, in this instance 3, co-axial wire rings, 1, 2 and 3 of substantially the same diameter and held in parallel spaced relation one above the other by a series of upright posts —4— which are spaced uniform distances apart circumferentially and are rigidly secured to each of said rings by spot welding or equivalent fastening means, thereby forming a rigid outer circular wall having relatively large openings between the

several rings and also between the posts through which the washing fluid may readily pass.

The lower ring —1— constitutes what may 5 be termed the base and is adapted to rest upon the outer marginal edge of a conical vat similar to that set forth in my pending application serial #454,631 filed March 23, 1921, although it is evident that it may 10 be otherwise supported within the vat if desired.

The intermediate ring —2— forms the outer marginal portion of an openwork bottom for receiving and supporting crockery 15 dishes and other utensils and for this purpose, different portions of opposite sides of the ring —2— are connected by diametrically extending tie-rods —5— crossing each other at the axis of the basket at uniform 20 angles and having their outer ends securely fastened to said ring at points uniform distances apart circumferentially for receiving and supporting a series of supplemental concentric rings —6— which are secured by 25 spot welding or otherwise to the upper faces of the radial tie-rods —5— in uniform spaced relation radially and coaxial with the axis of the basket so as to lie in proximately the same horizontal plane as the ring —2—, 30 thereby forming a series of relatively large openings between the tie-rods —5— and also between the rings —2— and —6—, the latter being spaced uniform distances from each other and also from the outer ring —2—.

35 The space between the openwork bottom as —7— and the top ring —3— is considerably greater than that between the bottom and lower ring —1— or of sufficient height above said bottom to confine the larger 40 size dishes within the basket when resting edgewise upon the bottom, it being understood that the rings 1 and 3 are secured respectively to the extreme lower and extreme upper ends of the posts —4— which are of 45 uniform height, thereby permitting the bottom ring or base —1— to rest flatwise upon a table or similar flat support for stability and strength, particularly when the basket is loaded with dishes. A circular guard rail 50 or supplemental ring —8— of substantially the same diameter as that of the rings 1, 2 and 3 is rigidly secured by a spot welding or otherwise to the posts —4— in a plane above and parallel with the bottom —7— coaxial 55 therewith for the purpose of confining smaller dishes within the basket when resting edgewise or otherwise upon the bottom —7—, said ring —8— being spaced from and between the rings —2— and —3— but 60 slightly nearer to the plane of the ring —2—.

The innermost ring —6— of the bottom wall —7— is of greater radius than the distance between the several rings —6— and forms a convenient bottom support for a central cylindrical cage —9— preferably of

perforated metal and held coaxial with the cage against lateral displacement by a series, of in this instance, three inverted U shape spring clasps —10— which are arranged equal distances apart circumferentially and 70 are secured at their lower ends by spot welding or otherwise to the innermost ring —6—, said clasps extending upwardly uniform distances from the bottom —7— to engage the periphery of the cage —9— when the latter 75 is placed in operative position.

The cage —9— rests loosely upon the innermost bottom ring —6— and is frictionally held in place by the spring clasps —10— but may be easily withdrawn and replaced 80 through the opened top of the basket when desired, said cage being adapted to receive knives, forks, spoons and other small articles and has its bottom and side walls perforated throughout their area to permit the 85 passage of water and other washing fluid therethrough, the top of the cage being normally extended some distance above the top of the rail —3— to permit it to be removed and reinserted without interference with the 90 dishes in other parts of the basket.

As a further means for reinforcing and stiffening the bottom —7— of the basket, the several rings thereof are connected together by additional radial tie-rods —11— which 95 are secured by spot welding or otherwise to said bottom rings in alternate relation to and midway between the radial arms of the tie-rods —5—.

It is now clear that the cage —9— and 100 outer rings —3— and —8— form the inner and outer walls of an intervening chamber of which the rings —2— and —6— and tie-rods —5— and —11— forms the bottom and that practically the entire chamber above 105 the bottom and between said inner and outer walls is available for said dishes, the majority of which are supported edgewise upon the bottom, and in order that they may be expeditiously and effectively cleansed by an 110 upward and circular whirl of the washing fluid, suitable means is provided for supporting the dishes in more or less systematic tangential relation to one or the other intermediate rings —6— or to some circle concentric therewith and for this purpose is 115 provided a series of substantially upright openwork partitions —12— arranged in uniform spaced relation circumferentially and extending inwardly and downwardly from the rings —3— and —8— across the greater portion of the dish receiving chamber in planes substantially tangential to one of the innermost rings —6— to which the downwardly projecting ends of the partitions are 120 rigidly secured by spot welding or other fastening means, the outer ends of the upper and lower parts of said partitions being secured by spot welding or equivalent means 125 to the rings —3— and —8—, respectively. 130

As illustrated, each partition —12— consists of an upper angular wire section —13— and a lower wire section —14—, the outer end of the upper section —13— being offset 5 circumferentially at —15— just inside of its point of securement to the ring —3— while the inner end of the same section is bent downwardly to form a vertical post —16—, having its lower end offset laterally at —17— just above its point of attachment to adjacent rings —6—, both offsets —15— and —17— being in the same direction so that the intervening portions may engage the concave faces of the plates and thereby prevent 15 contact of the edges of the plates with the partitions for the purpose of reducing to a minimum the liability of chipping said edges.

In other words, the portions of the wires 20 —13— and —16— between the offset ends —15— and —17— are all slightly convexed in the same general direction circumferentially of the basket while the plates and similar dishes which are placed edgewise upon 25 the bottom between the partitions are arranged with a concave side facing generally in the opposite direction whereby the convexed side of each partition will engage the concave side of the next adjacent plate at 30 that side, it being understood that the space between the adjacent partitions gradually increases from their inner ends toward their outer ends to allow the plates to separate more or less from each other when closely 35 stacked between the inner ends of the partitions and that these partitions serve to hold the plates in more or less tangential relation to the innermost rings with their concave sides facing in a direction opposite to that 40 of the whirling motion of the washing fluid. The offsets —17— at the lower ends of the posts —16— are disposed in approximately the same horizontal planes as that of the ring —8— and forms suitable seats for the 45 inner ends of the sections —14— of the partition where they are secured by spot welding or equivalent fastening means, the outer ends of the section —14— being secured by similar fastening means to the ring —8— 50 and extended downwardly and secured by spot welding to the underlying ring —2— thereby forming supplemental posts —18— for additionally supporting the circular 55 guard rail —8— in fixed relation to and above the bottom ring —2— for the purpose of holding the smaller dishes against lateral displacement when resting edgewise upon the openwork bottom of the basket and also for holding the lower edges of the larger 60 dishes from lateral displacement from said bottom.

The tie-rods —5— and —11— extend radially across the under sides of the several bottom rings —2— and —6— and in addition to being spot welded at the crossings

have their outer rings looped at —19— around the outermost ring —2— to additional strengthen the bottom of the basket, and also permitting the rings to present continuously smooth bearing surfaces for 70 the edges of the dishes throughout their lengths and thereby reducing to a minimum the chipping or breaking the edges of the dishes as they are moved along the rings.

The entire basket with the exception of 75 the cage —9— is preferably made of steel wire and in order that the liability of breaking or chipping of the dishes may be further reduced, the majority of the rings —6— between the cage —9— and outer 80 ring —2— where the edges of the larger dishes are more liable to rest, are covered by buffer rings —20— of wood fiber or other more or less resilient material capable of resisting the action of the washing fluid 85 and the wear of the dishes, the inner edge of the topmost ring —3— being covered by a similar buffer ring —21— for the same purpose, said buffer rings being preferably circular in cross section to reduce the area 90 of contact with the edges of the dishes.

The buffer rings —20— are secured in place to the underlying rings —6— by staples —22— or equivalent fastening means whereby the upper surfaces of the buffer 95 rings engaged by the dishes may be free from metal. (See Fig. 4.) The ends of the buffer rings —20— are spliced at —23— and secured together by staples —24—, the splices being preferably vertical while the 100 staples are driven through the ends horizontally between the upper and lower faces thereof so as to leave the upper faces free from metal.

The upper buffer ring —21— is held in 105 place against the inner ring —3— by means of loops —25— on the outer ends of the partition bar —13—, said loops serving to embrace both the rings —21— and —23— at substantially the same points, the buffer 110 rings being spliced horizontally at —26— and are arranged so as to be embraced by one of the loops —25— which holds the spliced ends in contact and against displacement without any further fastening 115 means.

The diametrically opposite sides of the upper ring —25— are provided with U shape wire handles —27— having their ends looped around both of the rings —23— 120 and —25— for hinged connection therewith whereby the handles may be dropped to any position from a vertical plane along the outside of the basket to a substantially horizontal plane over and upon the basket 125 where they are out of the way when the basket is placed in the vat of the washing machine.

The use of this invention will now be readily understood upon reference to the 130

foregoing description and the accompanying drawings and while the construction shown and described is preferable, it is evident that various details thereof may be 5 changed without departing from the spirit of the invention and therefore I do not wish to limit myself to the particular construction shown and described.

What I claim is:

- 10 1. A culinary basket comprising lower, intermediate and upper metal rings in vertically spaced relation, posts crossing said rings in circumferentially spaced relation and secured thereto at the crossings, additional metal rings within and spaced apart from the intermediate ring and from each other to form an openwork bottom, and tie-rods crossing said additional rings and secured thereto at their crossings and attached to the intermediate ring.
- 15 2. A cylindrical openwork basket having a series of partitions extending inwardly from its side walls in spaced relation circumferentially, each partition having the lower portion of its inner end offset circumferentially in one direction and secured to the bottom of the basket, and the outer end of its upper portion secured to the side wall of said basket.
- 20 3. A cylindrical openwork basket having a series of partitions extending inwardly

from its side walls in spaced relation circumferentially, each partition having the lower portion of its inner end offset circumferentially in one direction and secured 35 to the bottom of the basket, and the outer end of its upper portion offset in the same direction and secured to the side wall of said basket.

4. A culinary basket comprising a series 40 of spaced concentric rings, tie-rods extending radially across the undersides of said rings and secured thereto to form therewith an openwork bottom, upright posts secured to and extending some distance above and 45 below the outermost ring, additional rings secured to the posts in planes above and below and parallel with said bottom to form the sides of the basket, and a series of upright partitions arranged circumferentially 50 in spaced relation diagonally across said bottom rings and having their outer ends secured to one of the side rings and their inner ends secured to one of the bottom rings.

In witness whereof I have hereunto set my hand this 10th day of January, 1921.

WILLARD R. WALKER.
